UNITED STATES PATENT OFFICE.

WILLIAM P. CALLAHAN AND THOMAS DE ARMON, OF DAYTON, OHIO.

BOX FOR OIL-PRESSES.

SPECIFICATION forming part of Letters Patent No. 319,673, dated June 9, 1885.

Application filed May 4, 1885. (No model.)

To all whom it may concern:

Be it known that we, WILLIAM P. CALLAHAN and THOMAS DE ARMON, citizens of the United States, residing at Dayton, in the county of Montgomery and State of Ohio, have invented certain new and useful Improvements in Boxes for Oil-Presses, of which the following is a full, clear, and exact description, reference being had to the accompanying drawings, forming part of this specification.

Our invention relates to improvements in boxes for oil-presses, and has for its object the production of boxes better adapted to bear the necessary strain and pressure incidental to this class of presses, and it relates more particularly to that class of boxes known as "telescopic boxes."

Hitherto these boxes have been made of cast metal, and great difficulty has been encountered in their use by the frequent breakages that occur under the heavy pressure that is necessary, or else the boxes had to be made so heavy to avoid these breakages as to materially increase their cost without entirely obviating the liability of breaking.

The novelty of our invention consists in constructing the box essentially of wrought metal in separate pieces riveted or fastened together, as will be herewith set forth, and distinctly pointed out in the claims.

In the accompanying drawings, Figure 1 is a front end elevation through a tier of three boxes, the middle one of which is shown in section. Fig. 2 is a plan view of one of the boxes with the mat removed. Fig. 3 is a side elevation of Fig. 2. Fig. 4 is a detailed perspective view of one of the top pressure-plates.

The same letters of reference are used to indicate identical parts in all the figures.

A is the division-plate of the box, made of wrought metal, and preferably rectangular in form. Upon the top of this plate is secured a rail, B, of wrought angle-iron or steel, secured by rivets or bolts, and surrounding the two sides and front end of the plates.

Resting upon the plate A is a cast-metal block, C, which may be secured to the plate A by any means desired, and which forms the plunger on which rests the mat D, Fig. 1, of any suitable construction, that carries the meal from which the oil is to be expressed.

The space *a* between the rail B and the plunger C forms the gutter to receive the oil that is pressed from the meal, and conducts it into the trough or pocket E, provided with an outlet, *b*, that is bolted or otherwise fastened to the under side of the rear end of plate A.

To form the side and end walls of the box proper, we preferably employ angle-shaped steel plates F, which are partially recessed on their upper sides in the under side of the plate A, as seen at *c*, Fig. 1, so that the lateral strain is partially borne by the plate A, and is not thrown entirely upon the rivets or bolts which unite the side and end walls to the plate A.

The side and end walls of the box may be of separate pieces or of a single piece, as desired, and instead of steel, wrought angle-iron may be employed, though we consider steel the best and more durable.

To avoid the necessity of planing and polishing the under side of the plate A, forming the inside top of the box, we employ a separate brass or nickel plate, G, which fits snugly within the box, and may be fastened thereto, if desired, and which has its edges thickened to form beveled ribs *d* to fill the angular corners of the box, and to give the required shape to the edge of the meal-cake. This plate G has likewise projections *e* upon its under surface in the form of the heads of button-head bolts, which are provided to keep the cloth which incloses the meal from slipping when pressure is applied. These projections may be about two inches apart all over the lower surface of the plate G.

From the above construction it will be seen that we have produced a very simple telescopic box, which will bear an exceedingly heavy strain without liability of breaking, and which can be made much lighter than the ordinary cast-metal boxes.

Having thus fully described our invention, we claim—

1. A box for oil-presses, composed of a wrought-metal division-plate, A, supporting the plunger C, and to which is secured on its upper side an angle-iron gutter-rail, B, and on its lower side angle-shaped cast-steel side and end walls, substantially as described.

2. A box for oil-presses, composed of a wrought-metal division-plate, A, supporting

the plunger C, and to which is secured on its upper side an angle-iron gutter-rail, B, and on its lower side partially recessed angle-shaped side and end walls constructed of 5 wrought metal or steel, substantially as described.

3. In an oil-press box, the combination, with the inside top of the box, of polished metal

plates G, provided with projections e, substantially as and for the purpose described.
